OLIVER SALGEE, OF NEW YORK, N. Y.

Letters Patent No. 77,538, dated May 5, 1868; antedated April 25, 1868.

IMPROVEMENT IN PUMP-PISTONS.

The Schedule referred to in these Letters Patent and making part of the same.

TO ALL WHOM IT MAY CONCERN:

Be it known that I, OLIVER SALGEE, of the city and State of New York, have invented, made, and applied to use, a certain new and useful Improvement in Pump-Pistons; and I do hereby declare the following to be a full, clear, and exact description of the said invention, reference being had to the annexed drawing, making part of this specification, wherein—

Figure 1 is a vertical section of a pump with one of the pistons formed in the manner heretofore usual, and the other of my improved construction, and

Figure 2 is a sectional view at right angles to fig. 1, showing my improved piston.

Similar letters denote the same parts.

Pumps have heretofore been constructed with two cylinders, *a b*, upon a valve-box, having a hood or cap, *c*, enclosing the upper ends of the cylinders, with an exit at *d*, for the water, a rock-shaft, *e*, passing through stuffing-boxes, and receiving outside the hood *c*, pump-brake levers, by which the pump is operated, and within the hood, curved arms *f* are provided, with rollers entering horizontal slots in the slide and strap *g* of each piston. In this form there are considerable friction and wear, both on the piston and on the cylinder, because the roller bears first on one side, and then on the other, of the piston-strap, and hence the pump very quickly wears leaky, and has to be repaired, besides requiring considerable power to overcome friction.

The nature of my said invention consists in a forked link, combined with a piston-ring and valve, said piston-ring being formed with sockets, for receiving the ends of said forked link, so that the power exerted in moving the piston is applied to the same at a point inside of and between its upper and lower surfaces, so that there is little or no power lost in friction, and no tendency to bind the piston in the cylinder, or to produce an unequal wear in either the cylinder or the piston, and the space for the water-way and valve is not lessened.

k is my forked link, jointed at *i* to the lever-arm *f*, and at the ends *l l* to the ring *m*, forming the piston, said ring being made with sockets, for the reception of said joints *l l*; and pins *n*, passing through, on which the link *k* swings, to conform to the arc of a circle described by the joint *i*.

The valve *o* is applied to the upper face of the piston, and swings as usual, and the packing, *p*, is to be wound around the piston, in the recess formed for it.

What I claim, and desire to secure by Letters Patent, is—

The forked link *k*, in combination with the ring-piston *m*, that is formed with sockets, receiving the joints *l* of said link *k*, and with the valve *o*, applied between the forked link, as and for the purposes set forth.

In witness whereof, I have hereunto set my signature, this nineteenth day of June, A. D. 1867.

OLIVER SALGEE.

Witnesses:

GEORGE D. WALKER,

GEORGE T. PINCKNEY.
